Primary Examiner — Catherine Ho(74) Attorney, Agent, or Firm — Blank Rome LLP(57) CLAIM

I claim the ornamental design for a decal for a beverage bottle, as shown and described.

DESCRIPTION

FIG. 1 is a front view of a decal for a beverage bottle, showing my new design;

FIG. 2 is a right-side view thereof;

FIG. 3 is a left-side view thereof;

FIG. 4 is a top view thereof;

FIG. 5 is a bottom view thereof;

FIG. 6 is a front view of a decal for a beverage bottle shown in an environment of use;

FIG. 7 is a right-side view thereof;

FIG. 8 is a left-side view thereof;

FIG. 9 is a top view thereof;

FIG. 10 is a bottom view thereof; and,

FIG. 11 is a front view of a decal for a beverage bottle shown in another environment of use.

The broken lines in the drawings show environment that form no part of the claimed design.
